Attorney

UNITED STATES PATENT OFFICE.

PHILLIP J. DELL, JR., OF WAYCROSS, GEORGIA, ASSIGNOR TO W. J. GASSETT, OF WARE COUNTY, GEORGIA.

ENGINE-TIMER.

1,385,907.

Specification of Letters Patent. Patented July 26, 1921.

Application filed July 8, 1919, Serial No. 309,413. Renewed December 27, 1920. Serial No. 433,521.

To all whom it may concern:

Be it known that I, PHILLIP J. DELL, Jr., a citizen of the United States, residing at Waycross, in the county of Ware and State 5 of Georgia, have invented certain new and useful Improvements in Engine-Timers; and I do hereby declare the following to be a full, clear, and exact description of the invention, such as will enable others skilled 10 in the art to which it appertains to make and use the same.

This invention relates to new and useful improvements in attachments for internal combustion engines and has for one of its 15 objects the provision of means whereby the timer or commutator can be mounted for operation at a distant point from the end of the cam shaft and still be driven thereby instead of being located in close proximity 20 to the end of the cam shaft as at present thus obviating the inconveniences of manually lubricating the commutator or timer owing to its inaccessible location at present and its liability of interfering with the fan 25 and fan belt.

Another object of this invention is the provision of an attachment for internal combustion engines of the above stated character, which shall be simple, durable and efficient, and which may be manufactured and sold at a comparatively low cost.

With these and other objects in view as will become more apparent as the description proceeds, the invention consists in certain 35 novel features of construction, combination, and arrangement of parts as will be hereinafter more fully described and claimed.

For a complete understanding of my invention, reference is to be had to the following description and accompanying drawing, in which:—

Figure 1 is a front elevation of an attachment for internal combustion engines constructed in accordance with my invention 45 and illustrating the same applied to an engine,

Fig. 2 is a vertical sectional view of the attachment,

Fig. 3 is a detail view of the means for 50 securing the commutator or timer cap in place,

Fig. 4 is a transverse sectional view taken 55 through the timer cap or shell illustrating the contact roller and the manner of mounting the same.

Referring in detail, the numeral 1 indicates a cover plate for the timing gears of the engine 2 and is of the usual construction having an opening 3 to receive the end of the cam shaft 4 on which is mounted a bevel gear 5. Formed upon the cover 1 and about the opening 3 is a housing 6 provided with a removable cover 7. The housing 6 has an upwardly and outwardly extending tubular member 8 formed thereon having located 60 in each end bearings 9 that rotatably support a shaft 10. The shaft 10 has a bevel gear 11 secured to one end and located within the housing 6 and in mesh with the gear 5. The tubular member 8 is supported 65 in an upwardly inclined position by means of brackets 12 which is secured to the cover plate 1. An annular member 13 is formed on the upper end of the tubular member 8 and is adapted to form a seat for a commutator shell 14 of an ordinary construction provided with the usual contact 14'. The upper end of the shaft projects beyond the annular member 13 within the shell and has mounted 70 or secured thereto a contact roller 15. The 75 contact roller 15 is mounted or journaled to one end of an arm 16 that is pivoted between a pair of arms 17 formed on the collar splined or otherwise secured to the upper end of the shaft. The arm 16 has a spring 80 85 secured to its other end which spring is in turn connected to a lug formed upon the collar. The apex of the shell is provided with the usual recess 20 to receive one end of a locking rod 21. The locking rod 21 is 90 slidably mounted within apertured lugs 22 formed upon the tubular member 8 and is offset as clearly shown in the drawing so that said rod can extend about the annular portion 13 and the shell to engage in the 95 recess 20. A coil spring 23 is mounted upon the rod 21 between the lugs 22 and has one end secured to the rod while its other end bears against one of the lugs so that said rod is placed under tension for securely holding 100 the shell against the annular portion.

From the foregoing description taken in connection with the accompanying drawing, it will be noted that the timer or distributor is mounted at a convenient point whereby 105 necessary repairs can be conveniently made to the same and also can be easily lubricated when desired. It is also to be noted that the device can be readily applied to an internal combustion engine of a certain type without 110

altering the construction and operation of the engine.

While I have shown and described the preferred embodiment of my invention, it will be understood that minor changes in construction, combination, and arrangement of parts may be made without departing from the spirit and scope of the invention as claimed.

10 Having thus described my invention, what I claim is:—

An attachment for engines including a timing gear cover and a cam shaft, a housing formed on the cover, a tubular member

15 formed on said housing, a timing shaft journaled in said tubular member and housing

and connected to the cam shaft, an annular portion formed on the upper end of the tubular member, a timer shell mounted on said annular portion, a contact roller carried by 20 the timing shaft and operating within the shell, spaced apertured lugs formed on the tubular member, a spring actuated locking rod mounted in said lugs and having its free end curved to engage the shell. 25

In testimony whereof I affix my signature in presence of two witnesses.

PHILLIP J. DELL, JR.
